UNITED STATES PATENT OFFICE.

JOSIAH WILLIAM BUZZELL, OF EAST ORANGE, NEW JERSEY, AND WILLIAM H. LARKIN, JR., OF WORCESTER, MASSACHUSETTS.

CONCRETE-CONVEYER.

No. 894,813.

Specification of Letters Patent.

Patented Aug. 4, 1908.

Application filed June 13, 1907. Serial No. 378,697.

To all whom it may concern:

Be it known that we, JOSIAH WILLIAM BUZZELL and WILLIAM H. LARKIN, Jr., citizens of the United States, and residents, respectively, of East Orange, in the county of Essex and State of New Jersey, United States of America, and of Worcester, in the county of Worcester and State of Massachusetts, United States of America, have invented certain new and useful Improvements in Concrete-Conveyers, of which the following is a specification.

Our invention relates to an apparatus for and method of conveying concrete or other material.

We will describe our invention in the following specification and point out its novel features in claims.

Referring to the drawings, Figure 1 is a side elevation, partly in section, of an apparatus which we have designed for carrying our invention into effect. Fig. 2 is a side elevation, partly in section, of an arrangement for handling and conveying material in larger quantities. Fig. 3 shows in cross-section a pressure-controlling valve which may be used in conjunction with the arrangement of parts shown in Fig. 2. Fig. 4 is an elevation of another form of our invention, showing a manner in which the apparatus may be used for conveying material to considerable distances. Fig. 5 is a plan view of some of the parts shown in Fig. 4.

Like characters of reference designate corresponding parts in all of the figures.

10 designates a concrete mixer of well-known construction; 11 is its charging and 12 its discharge chute. This is operated in the usual way and is arranged to discharge into a hopper 20, the lower end of which is sealed by a plate 21. This plate is pivoted at 22 and is held up against the lower end of the hopper by a weighted arm 23 which may be placed inside the hopper if desired, or outside 45 of the hopper as shown so that it may be manually operated.

Below the hopper 20 is a pressure chamber 25 which, for convenience of manufacture, may be in alinement with and of the same 50 shape as the hopper 20 so that the same parts may form the sides of both the hopper and the pressure chamber. A discharge pipe 26 is connected with the pressure chamber, preferably at its lower end, and if desired, a valve 30 may be placed in this pipe.

31 designates a lever which is connected with the valve 30 and by means of which the valve may be operated.

35 is a condenser chamber in the pipe 26 below the valve 30.

40 designates a pipe from a suitable source of fluid pressure supply such, for example, as steam or compressed air. This pressure pipe is connected with the pressure chamber 25 at 41 at a point preferably above the seal of the hopper. A controlling valve 42 in the pipe 40 provides means for turning the pressure into or shutting it off from the pressure chamber 25.

43 designates a relief pipe and 44 a manually operated valve in this pipe.

At 45 is shown a pressure gage connected with the pressure chamber 25.

50 is a water supply pipe which is connected with the lower end of the pressure chamber 25, and 51 is a valve in this pipe to shut off the pipe or to control the flow of water through it. A nozzle 52 within the condenser chamber is connected with the water supply by a pipe 53 which is controlled by a valve 54. The nozzle 52 is also connected with the steam or air pressure supply by a pipe 46 in which is a controlling valve 47.

Before describing the other parts of our invention which we have illustrated we will point out the operation of the apparatus which we have already described.

The matter to be conveyed is first placed in the hopper 20. If the apparatus is to be used for conveying concrete the various ingredients which form the concrete are placed in the mixer 10, and from thence are discharged into the hopper in semi-liquid condition and designated in the drawings by the character X. In the beginning of the operation the valves 30 and 42 may be closed and the mixed concrete allowed to pass directly into the pressure chamber 25 by opening the seal 21. If the valve 30 is closed this will stop the outward flow of the material so that the concrete will fill the pressure chamber. When a sufficient quantity of concrete has thus been placed within the pressure chamber, the seal 21 is closed, the discharge-controlling-valve 30 opened, and valve 43 opened to admit pressure from the source of pressure supply to the pressure chamber. This will cause the material within the pressure chamber to be forced out through the discharge pipe 26.

A jet of steam may be forced into the chamber 35 and this will be followed by a condensation which will produce a partial vacuum into which the concrete from the 5 pressure chamber will be drawn. This will prevent arching of the concrete in the lower contracted end of the pressure chamber and will facilitate the operation of the apparatus. The jet of steam which is introduced into the 10 chamber 35 under pressure will also tend to carry along the moving mass within the discharge pipe and thus act as a booster. Water under pressure may be also forced into the condenser chamber and this will prevent 15 the semi-liquid concrete setting and will also aid in forcing it through the discharge pipe.

We also provide means for introducing water into the lower end of the pressure chamber 25 through the water pipe 50 in order to 20 prevent setting and arching of the concrete at the lower contracted portion of the pressure chamber. This water connection also furnishes means for filling the lower part of the pressure chamber with water when not in 25 use, thus keeping the parts clean and preventing them from becoming incrusted with and clogged up by hardened concrete. The water may also be forced out of the pressure 30 chamber by steam or air pressure or under its own pressure, through the valve 30, condenser chamber 35 and discharge pipe 26 to flush these parts and cleanse them.

While the part of the operation above described is taking place, the hopper 20 may be 35 gradually filled from the mixer 10 so that as soon as the material in the pressure chamber has been forced out as described, a new supply of material may be quickly placed within the pressure chamber by opening the seal 21. 40 Before doing this the valve 42 is closed to shut off the pressure supply from the pressure chamber and it may be necessary to open the valve 44 to release the pressure, as the pressure within the chamber has a tendency 45 to maintain the seal in its closed position. The apparatus may be worked satisfactorily without the use of the valve 30 in the discharge pipe but in many cases we find it advantageous to place a valve in the pipe 50 not only for facilitating the part of the operation which we have above described, but for controlling the quantity of material supplied at the discharge point.

In Fig. 2 we have illustrated a modification of our invention. In this case two hoppers 20 and 20^A are used. The mixer 10 in this case is so situated that it will discharge directly into the hopper 20. A chute 13 is provided, however, to lead the concrete discharged from the mixer into the hopper 20^A when desired. The upper section 14 of this chute is pivoted at 15 as shown, and is provided with an actuating lever 16 by means of which the section 14 may be moved away 65 from the discharge chute 12 of the mixer.

The lower end of the hopper 20 is sealed in the manner before described. 21^A, 23^A and 25^A designate corresponding parts under the other hopper 20^A. The discharge pipe from the pressure chamber 25^A is designated in 70 this case by the numeral 27. The discharge pipes 26 and 27 from the two pressure chambers are connected through a common condenser chamber 35^A to a discharge pipe 28. The nozzle 52^A within this condenser chamber 75 may be connected with the fluid pressure supply pipe 40 by a pipe 46, or with water supply pipe 50 by pipe 53 as in the previous case. 32 is a valve in the discharge pipe 27. It may be placed in alignment with the valve 80 30 and the pistons of both valves supported upon a common piston rod 32^A. A connecting rod 33 is arranged to connect this piston rod with a bell-crank lever 34 which is pivoted at 34^A and arranged to be moved by an 85 actuating rod 36. The water supply pipe 50 is shown connected with the lower portions of both pressure chambers 25 and 25^A, and two controlling valves 51 and 51^A are provided as shown. Between the two pressure 90 chambers, a valve 60 is placed. This valve comprises two pistons 61 and 62 mounted upon a common piston rod 63. The pressure pipe 40 is connected with this valve at its central portion. A pipe 64 is connected with the 95 pressure chamber 25 and with the valve 60 through the ports 65 and 66. 67 is a pipe connecting the pressure chamber 25^A with the valve 60 through the ports 68 and 69. 70 designates a manually operated crank by 100 means of which and a pinion 71 a controlling gear 72 may be rotated. 17 designates a connecting rod which is arranged to connect the chute actuating lever 16 concentrically with the controlling gear 72. The actuating 105 rod 36 for valves 30 and 32 is similarly connected with the controlling gear 72, as is also a connecting rod 63^A between the controlling gear and the valve 60. In operating this form of our invention, when the parts are in 110 the position shown in Fig. 2, the semi-liquid concrete or other material in the pressure chamber 25 is being forced out through discharge pipe 26, through valve 30, and into and through condenser chamber 35^A and the 115 discharge pipe 28. The hopper 20 is shown filled, and the concrete from the mixer 10 is being discharged into the hopper 20^A and pressure chamber 25^A. During this part of the operation, pressure supply pipe 40 is connected with the pressure chamber 25 through the port 66 of the valve 60 and the pipe 64, at the same time, the pressure from pressure chamber 25^A is released through pipe 67 and port 68 of the valve 60. The parts may be 120 so arranged that the weighted lever 23^A is not sufficiently heavy to cause the seal 21^A to remain closed when the additional weight of the concrete in the hopper 20^A is placed upon it if there is no pressure within the pressure 125 130

chamber 25^a. As soon as the concrete in the pressure chamber 25 has been forced out, an operator may cause the controlling gear 72 to make half a revolution which will cause the valve 30 to be closed, the valve 32 to be opened, pressure from pressure chamber 25 to be released through pipe 64 and port 65 of valve 60, and at the same time will cause pressure to be admitted to pressure chamber 25^a through port 69 and pipe 67. The upper section 14 of chute 13 will be moved away from the discharge chute 12 of the mixer 10 so that the concrete issuing therefrom will flow into hopper 20 and through seal 21 into pressure chamber 25. The pressure now admitted to pressure chamber 25^a will cause the seal 21^a to be automatically closed and will cause the concrete in this pressure chamber 25^a to be forced out through discharge pipe 27, valve 32, into and through the condenser chamber 35^a and discharge pipe 28. In this manner a practically continuous flow of concrete may be forced through the discharge pipe 28 to the desired point of delivery, and a very large quantity of material may thus be conveyed during a given time in a simple manner.

In Figs. 4 and 5 we have shown another manner of carrying out our invention. In this case the mixer 10 is placed midway between the two hoppers and pressure chambers, and the concrete discharged from the mixer is led directly into one or the other of the pressure chambers or into the hoppers above them by a pivoted chute 14^a. Beyond the condenser chamber 35^a other condenser chambers 35^b and 35^c are shown in the discharge pipe 28. All the condenser chambers may be connected with the pipes 40 and 50 as shown. Our apparatus may be used successfully for conveying material to considerable distances without the aid of these condenser chambers, but as these serve the purpose of preventing the concrete from setting during the operation, and also act as boosters, it may be seen that the discharge pipe may be extended any desired length and that material may be conveyed great distances through it. The pipe line may be provided at intervals with sections 29 of flexible material so that it may be shifted without interrupting its service. Its outer end 28^a may be flexible and provided with the discharge nozzle 28^b, and the valve 28^c may be placed near the point of discharge to facilitate the handling of the conveyed material at the point of discharge. By this apparatus the mixed concrete may be carried any distance from the mixer to the desired point of discharge and may be discharged directly into molds or forms. Thus a great saving of time and labor is accomplished and advantages gained over former methods used, such as by buckets, wheelbarrows, carts, hoists, derricks or telpherage systems. The con-

crete may be discharged under pressure, and consequently it may be readily carried into tunnels or caissons which are under pressure and to other places which are not readily accessible.

We have illustrated more than one form of our invention to show that we do not limit ourselves to any specific mechanism or apparatus for carrying it into effect, and it is, of course, obvious that our invention is applicable for conveying other material than concrete.

What we claim is.—

1. The combination of a hopper, a chamber, a removable seal between the hopper and the chamber, a discharge pipe connected with the chamber, and means for maintaining pressure within the chamber.

2. The combination of a hopper, a chamber, a removable seal between the hopper and the chamber, a discharge pipe connected with the chamber, means for maintaining pressure within the chamber, and means for releasing the pressure within the chamber.

3. In a conveyer, a chamber, a hopper, a removable seal between the hopper and the chamber, a discharge pipe connected with the lower portion of said chamber, a valve in the discharge pipe, a pressure pipe connected with the upper portion of the chamber, and a valve in the pressure pipe.

4. The combination of a pressure chamber, a discharge pipe connected with said chamber, means for introducing pressure into the pressure chamber, and additional means for directly introducing pressure into the discharge pipe.

5. In a conveyer, a chamber, a hopper, a removable seal between the hopper and the chamber, a discharge pipe connected with said chamber, means for introducing pressure into the chamber, and means for introducing pressure into the discharge pipe.

6. In a conveyer, a chamber, a hopper, a removable seal between the hopper and the chamber, a discharge pipe connected with said chamber, and a pressure pipe connected with the chamber and with the discharge pipe.

7. In a conveyer, a pressure chamber, a hopper, a removable seal between the hopper and the chamber, a discharge pipe connected with the lower portion of said chamber, a valve in the discharge pipe, a pressure pipe connected with the upper portion of the chamber and with the discharge pipe, a valve in the pressure pipe in its connection with the pressure chamber, and a valve in the pressure pipe in its connection with the discharge pipe.

8. In a conveyer, a pressure chamber, means for introducing semi-liquid material into the chamber, means for introducing pressure into said chamber and thereby forcing said material out of the chamber, a dis-

70

charge pipe for conveying the material away from the chamber, and a condenser chamber in the discharge pipe.

9. In a conveyer, a chamber, a hopper, a seal between the hopper and the chamber, a discharge pipe connected with said chamber, means for introducing pressure into the chamber, a condenser chamber in the discharge pipe, means for introducing steam into said condenser chamber, and means for introducing water into said condenser chamber.

10. In a conveyer, a chamber, a hopper, a removable seal between the hopper and the chamber, a discharge pipe connected with the lower portion of said chamber, a condenser chamber in the discharge pipe, a pressure pipe connected with the upper portion of the chamber, means for introducing steam into the condenser chamber, and means for introducing water into the condenser chamber.

11. In a conveyer, a pressure chamber, a discharge pipe connected with said pressure chamber, a steam pipe connected with the pressure chamber and with the discharge pipe, and a water pipe connected with the pressure chamber and with the discharge pipe.

12. In a conveyer, a chamber, a hopper, a removable seal between the hopper and the chamber, a discharge pipe connected with said chamber, a pressure pipe connected with the chamber, and a water pipe connected with the chamber.

13. In a conveyer, a pressure chamber, a discharge pipe connected with said pressure chamber, a condenser chamber in the discharge pipe, a steam pipe connected with the pressure chamber and with the condenser chamber, and a water pipe connected with the pressure chamber and with the condenser chamber.

14. In a conveyer, a pressure chamber, a discharge pipe connected with the pressure chamber, a pressure pipe connected with the pressure chamber, and connections between the pressure pipe and the discharge pipe at intervals along the length of the discharge pipe.

15. The combination of a plurality of pressure chambers, a discharge pipe, connections between the lower ends of the chambers and the discharge pipe, a valve in each of said discharge connections, a pressure pipe connected with the upper portions of the pressure chambers, a valve between the pressure pipe and each of the chambers, and means for actuating the valves for introducing pressure into any one of the chambers and for opening the valve in the discharge connection of the same chamber.

16. The combination of a plurality of hoppers, a plurality of chambers associated therewith, a removable seal between each hopper and its respective chamber, a discharge pipe

connected with each of the chambers, and means for alternately introducing pressure into one or another of the chambers.

17. The combination of a plurality of hoppers, a plurality of chambers associated therewith, a removable seal between each hopper and its respective chamber, a discharge pipe, a connection between the lower portion of each chamber and the discharge pipe, a valve in each of said discharge connections, a pressure pipe connected with the upper portion of the chambers, a valve between the pressure pipe and its connection with each of the chambers, and means for actuating the valve to connect the pressure pipe with any one of the chambers, to open the valve in the discharge connection of the same chamber, and to close the valve in the discharge connections of the others of said chambers.

18. The combination of a plurality of hoppers, a plurality of chambers associated with the hoppers, a counterbalanced seal between each hopper and its respective chamber, a discharge pipe, a connection between the lower portion of each chamber and the discharge pipe, a valve in each of said discharge connections, a pressure pipe connected with the upper portion of each of said chambers, a valve between the pressure pipe and its connections with each of the chambers, said valves being arranged to introduce pressure into one or another of the chambers and to release the pressure from the others of said chambers, and means for actuating the pressure pipe valves and the discharge connection valves together.

19. The combination of a plurality of pressure chambers, a discharge pipe, connections between the lower ends of the chambers and the discharge pipe, a valve in each of said discharge connections, a condenser chamber in the discharge pipe, a steam pipe connected with the upper portions of the pressure chambers and with the condenser chamber, a valve between the steam pipe and each of the chambers, and means for actuating the valves for introducing pressure into any one of the chambers and for opening the valve in the discharge connection of the same chamber.

20. The combination of a plurality of pressure chambers, a discharge pipe, connections between the lower ends of the chambers and the discharge pipe, a valve in each of said discharge connections, a condenser chamber in the discharge pipe, a steam pipe connected with the upper portions of the pressure chambers and with the condenser chamber, a water pipe connected with the lower portions of the pressure chambers and with the condenser chamber, a valve between the steam pipe and each of the chambers, a valve between the water pipe and each of the chambers, and means for actuating the valves for

introducing pressure into any one of the chambers, and for opening the valve in the discharge connection of the same chamber.

21. The combination of a plurality of pressure chambers, a discharge pipe, connections between the lower ends of the chambers and the discharge pipe, a valve in each of said discharge connections, a plurality of condenser chambers in the discharge pipe, a 10 steam pipe connected with the upper portions of the pressure chambers and with the condenser chambers, a water pipe connected with the lower portions of the pressure chambers and with the condenser chambers, a 15 valve between the steam pipe and each of the chambers, a valve between the water pipe

and each of the chambers, means for actuating the valves for introducing pressure into any one of the chambers, and for opening the valve in the discharge connection of the same 20 chamber, flexible joints in the discharge pipe and a flexible discharging end on the discharge pipe.

In testimony whereof we have signed our respective names to this specification in the 25 presence of two subscribing witnesses.
